(57) **CLAIM**

The ornamental design for wind turbine nacelle as shown and described.

DESCRIPTION

FIG. 1 is a front perspective view of a wind turbine nacelle showing the new design.

FIG. 2 is a rear perspective view of the wind turbine nacelle.

FIG. 3 is a front view of the wind turbine nacelle.

FIG. 4 is a rear view of the wind turbine nacelle.

FIG. 5 is a top view of the wind turbine nacelle.

FIG. 6 is a bottom view of the wind turbine nacelle; and,

FIG. 7 is a right side view of the wind turbine nacelle, the left side being a mirror image thereof.

1 Claim, 7 Drawing Sheets
